UNITED STATES PATENT OFFICE.

ANTON BECKER, OF COLUMBUS, OHIO, ASSIGNOR TO THE RALSTON STEEL CAR COMPANY,
OF COLUMBUS, OHIO.

END CONSTRUCTION FOR RAILWAY-CARS.

No. 865,854.

Specification of Letters Patent.

Patented Sept. 10, 1907.

Application filed May 10, 1907. Serial No. 372,938.

To all whom it may concern:

Be it known that I, ANTON BECKER, of Columbus, in the county of Franklin and State of Ohio, have invented certain new and useful Improvements in End 5 Constructions for Railway-Cars; and I do hereby declare the following to be a full, clear, and exact description of the invention, such as will enable others skilled in the art to which it appertains to make and use the same.

10 My invention relates to an improvement in the end construction of railway cars, and more particularly to an improved end plate or buffing block,—the object of the invention being to obviate the use of a sheet metal end plate such as heretofore commonly employed, 15 and to provide an end plate or buffing block which shall be strong and substantial in construction and which will be capable of withstanding all strains to which it may be subjected without liability of injury to said plate or block or to the structure behind it.

20 With this object in view, the invention consists in certain novel features of construction and combinations and arrangements of parts as hereinafter set forth and pointed out in the claims.

In the accompanying drawings: Figure 1 is a view of 25 a portion of the end of a car, showing the application of my improvements thereto; Fig. 2 is a sectional view of the same; Fig. 3 is a view in section on the line $x-x$ of Fig. 1; Fig. 4 is a perspective view of my improved buffing block, showing the rear side thereof, and Fig. 5 is a 30 sectional view of a portion of a bar and showing a modification of the buffing block.

1 represents the end sill of a car underframe; 2, 2, the end stakes, and 3, 3 the draft sills.

4 represents my improved end plate or buffing block, 35 which is a casting having a wide upper portion 5 provided with a series of holes 6 for the passage of bolts 7 which secure the buffing plate or block to the end sill 1 as shown in Figs. 1 and 2. The wide upper portion of the plate or block, is provided on its front face with a 40 series of parallel strengthening ribs 7, and ribs 8 project rearwardly from the rear face of the wide upper portion of the plate or block and are disposed under the end sill 1 as shown in Fig. 2. If desired, the plate or block may be provided with a rearwardly projecting flange 9, as shown in Fig. 5, disposed under the lower flange of the end sill 1 and riveted thereto. The ribs 8 are connected by a horizontally-disposed rib or flange 10 at the base of the upper wide portion of the plate or block, and extending downwardly from the rib or flange 50 10 at the side edges of the intermediate portion of the plate or block, are rearwardly projecting ribs or flanges 12. These vertical flanges or ribs 12, connect, at their

lower ends, with horizontal flanges or ribs 13 which project rearwardly from the wide lower or base portion 14 of the plate or block.

55 The draft sills 3 are disposed at the respective sides of the narrower or intermediate portion of the plate or block and are secured to the vertical ribs or flanges 12 thereof, by means of rivets 15. The forward ends of the draft sills have their lower portions cut away, so as to permit said forward ends of the draft sills to rest upon the horizontal ribs 13, and bracing webs 16 connect the flanges or ribs 13 with the front member of the plate or block at respective ends of the base portion of the latter.

60 The plate or block is made with an opening 17 for the accommodation of the draft appliances, and just over this opening a horizontally-disposed rib or flange 18 projects from the rear face of said plate or block, and is connected at the center with the horizontal flange or 65 rib 10 by means of short, vertically-disposed flange or rib 19.

A rest bar 20 for the draft appliances, is made in the form of an angle bar and extends across the lower portion of the opening 17,—the ends of this bar being secured to the base portion of the plate or block by means 70 of bolts 21, and to the horizontal flanges or ribs 13 by means of bolts 22.

75 Various slight changes might be made in the details of construction of my invention without departing 80 from the spirit thereof or limiting its scope and hence I do not wish to limit myself to the precise details herein set forth.

Having fully described my invention, what I claim as new and desire to secure by Letters Patent is:

85 1. An end plate or buffing block for a car, comprising a casting adapted for attachment to the end sill of the car and provided at its upper portion with forwardly projecting ribs, said casting also having rearwardly projecting flanges or ribs for attachment to the draft sills of the car.

90 2. An end plate or buffing block for a car, comprising a casting adapted for attachment to the end sill of a car and provided with ribs or flanges projecting rearwardly so as to be disposed under said end sill, two of said ribs or flanges affording attaching means for the plate or block to 95 the draft sills of the car.

3. An end plate or buffing block for a car, comprising a casting having an opening for the accommodation of the draft devices, and provided with rearwardly projecting, horizontally-disposed ribs or flanges above said opening and with vertical ribs connecting said horizontal ribs, two of said vertical ribs affording means for the attachment of the plate or block to the draft sills of the car.

100 4. An end plate or buffing block for a railway car, comprising a casting adaptable for attachment to the end sill of a car and having an opening for the accommodation of the draft devices, said casting having horizontally-disposed ribs or flanges projecting rearwardly therefrom over the

base portion thereof, an angle bar behind the front face of the casting extending across the lower portion of the opening in the casting, and fastening devices securing said angle iron bar to the rear face of the casting and to said horizontally disposed flanges.

B. The combination with the end sill and draft sills of a car, the latter having recessed forward ends, of an end plate for bolting block secured to and depending from the end sill and having its intermediate portion secured to the draft sill and its base extending through the recessed

portions of the draft sills, and a bar secured to said base portion and extending across the opening in the plate or block through which the draft devices pass.

In testimony whereof, I have signed this specification in the presence of two subscribing witnesses.

ANTON BECKER.
